UNITED STATES PATENT OFFICE

149,678

DESIGN FOR A FLOOR FAN

Joseph T. Roffy, Los Angeles, Calif.

Application December 9, 1946, Serial No. 135,353

Term of patent 14 years

(Cl. D26—7)

To all whom it may concern:

Be it known that I, Joseph T. Roffy, a citizen of the United States, residing at Los Angeles, in the county of Los Angeles and State of California, have invented a new, original, and ornamental Design for Floor Fan, of which the following is a specification, reference being had to the accompanying drawing, forming a part thereof.

Fig. 1 of the drawing is a top view of a floor fan embodying my new design;

Fig. 2 is a side elevational view of the floor fan of Fig. 2;

Fig. 3 is an enlarged perspective view of the top portion of the floor fan showing the attachment of the radial fins to a central plate, and showing portions of the handle broken away; and

Fig. 4 is an enlarged perspective view of one of the grill segments illustrated in elevation in Fig. 2.

I claim:

The ornamental design for a floor fan, as shown and described.

JOSEPH T. ROFFY.
